UNITED STATES PATENT OFFICE.

LEON E. HIRT, OF PITTSBURGH, PENNSYLVANIA.

METHOD OF AND APPARATUS FOR THE MANUFACTURE OF PRODUCER-GAS.

1,130,512.

Specification of Letters Patent.

Patented Mar. 2, 1915.

Application filed February 25, 1913. Serial No. 750,506.

To all whom it may concern:

Be it known that I, LEON E. HIRT, a citizen of the United States, residing at Pittsburgh, in the county of Allegheny and State of Pennsylvania, have invented a new and useful Improvement in Methods of and Apparatus for the Manufacture of Producer-Gas, of which the following is a full, clear, and exact description, reference being had 10 to the accompanying drawings, forming part of this specification, in which—

Figure 1 is a central vertical section of a gas producer unit embodying my invention; Fig. 2 is an end view of the same; Fig. 3 is a section on the line III—III of Fig. 1; Fig. 4 is a cross section of the reduction passage or conduit; Fig. 5 is a view similar to Fig. 1, but showing a modification; Fig. 6 is a section on the irregular line VI—VI of Fig. 5; and Fig. 7 is a cross section of the reduction passage or conduit of Figs. 5 and 6.

My invention has relation to the manufacture of producer gas and is more especially 25 designed to provide a method of and apparatus for the manufacturer of such gas from crude oil, although my invention may also be used to good advantage in the manufacture of gas from pulverized coal, lignite, 30 iron pyrites, and other carbonaceous material.

My invention provides a method and apparatus whereby a superior quality of gas may be manufactured at a relatively low cost 35 of operation.

It also provides gas producer units of compact form and of relatively inexpensive construction.

The nature of my invention will be best 40 understood by reference to the accompanying drawings, which will now be described, it being premised, however, that various changes may be made both in the details of the apparatus and the details of the method, 45 without departing from the spirit and scope of my invention as defined in the appended claims.

Referring first to that form of my invention which is shown in Figs. 1 to 4, inclusive, 50 the numeral 2 designates the outer metal shell of a gas producer unit, the shell being shown as of cylinder form; 3 designates the combustion chamber of the unit which is formed within the refractory walls 4, built 55 within the shell 2. 5 designates an oil burner of the injector type, which is ar-

ranged to inject oil and steam into the combustion chamber 3. This burner may be, in general, of any suitable character to inject the oil in comminuted or spray form into the combustion chamber. 6 designates air inlet openings, the area of which may be controlled by a suitable adjustable damper 7. The upper portion of the combustion chamber is preferably contracted by stepping in the sidewalls thereof, as indicated at 8, and above this contracted portion the upper portion of the chamber is preferably expanded laterally by stepping out the side walls, as indicated at 9. This expansion of the upper portion of the combustion chamber is preferably sufficient to permit of a very considerable increase in the volume of the products of combustion. In practice, I have found it advisable to permit the gases to 70 expand in this portion of the chamber to a volume some three or four times their initial volume. The extreme upper portion of the chamber is again contracted in the direction of the length of the unit by stepping in the 80 walls, as indicated at 10, this in-stepping being opposite the rear end of a contracted passage 11. This passage 11 opens at its forward end into another expansion chamber 12. The area of this chamber 12 is sufficient to permit of another large expansion 85 in the volume of the gases. In practice, I have obtained good results by making the chamber 12 of a size to permit the gases to expand to a volume some ten or twelve times 90 their initial volume. The numeral 13 is an outlet opening in the forward wall of the chamber 12, which communicates with an elongated reduction passage or conduit 14, 95 extending longitudinally of the unit and out through the forward end thereof. This passage or conduit is of a relatively small cross sectional area, but is of very considerable length. The forward end of this conduit opens into a vertical discharge nozzle 15 100 which may be of any suitable ejector type, such as a Koerting nozzle, and containing a steam jet 16. The nozzle 15 extends downwardly into the water tank 17, into which it discharges below the surface of the water, 105 the gas escaping through the outlet 18, leading to the usual washer. The space within the unit around the refractory brickwork containing combustion chamber 3, expansion chamber 12 and the reduction passage or 110 conduit 14, may be filled with a suitable material, such as cinder, as indicated at 19. 20

designates a sight hole opening into the upper part of the combustion chamber 3.

The operation is as follows: The oil is sprayed into the lower portion of the combustion chamber 3, the burner 5 being preferably directed to cause a discharge at an upward angle. The combined spray of oil and steam impinges against the opposite wall of the chamber 3, resulting in the breaking up of the oil. The combustion at once takes place, the products of combustion rising between the contracting walls 8, the steps or offsets of which serve to impart a more or less swirling movement. This results in a better mixing of the gases. These gases pass into the enlarged intermediate portion of the combustion chamber where a sudden expansion takes place, resulting in a still further commingling and mixing thereof. The gases are again contracted in passing through the extreme upper portion of the combustion chamber and through the conduit 11. Escaping from this conduit 11 into the chamber 12, a second expansion occurs with increased velocity, whereby the gases are caused to impinge against the walls of the chamber and a further mixing and commingling takes place. The gases then pass into and through the reduction passage or conduit 14. The C_nH_n+2 compounds present in these gases causes a constant deposit of carbon upon the walls of this passage which are maintained at a very high heat by the gases passing therethrough. This temperature is preferably not less than 600° C. This carbon, which is in a more or less incandescent state, acts to reduce the carbon dioxide (CO_2) passing through the conduit to carbon monoxide (CO). The provision of the surrounding body of heat-insulating material, such as indicated at 19, greatly facilitates the maintenance of the proper temperature in the reduction passage or conduit, as well as a practically uniform temperature throughout its length. This passage or tube is substantially horizontal, although preferably slightly inclined downwardly toward its discharge end. I have discovered that a much better contact of the gases with the carbon deposited on the walls of the tube can be obtained in a substantially horizontal passage than is possible in a vertical passage. As the gases are discharged from the forward end of the conduit 14, they are met by the steam from the jet 16 and act upon this steam to decompose it with the accompanying formation of hydrogen and carbon monoxide. The gases then pass through the wash box or tank 17, thence to the outlet 18.

The producer may be operated either upon a pressure or suction system. The provision of the elongated conduit or passage 14 of contracted cross sectional area constitutes an important feature of my invention,

especially in connection with the expansion chambers traversed by the gases before entering this passage. Preferably, this passage, together with the combustion and expansion chambers, is so proportioned that each unit volume of gas will be retained in the producer, before escaping from the passage 14, at least three seconds, although this time may be increased. The provision of this elongated contracted passage insures an intimate contact between the gases and the walls of the passage, whereby a maximum reduction of carbon dioxide is effected and the gases become thoroughly fixed. In the larger sizes of units, instead of increasing the cross sectional area of the passage 14 to the extent which would be necessary in order to enable it to carry off the gases with sufficient rapidity, I preferably provide two or more of these passages arranged side by side, as shown at 14^a, in Figs. 6 and 7. In this manner, each of the passages may be kept of proper size to give the desired wall or contact area in proportion to the volume of gas passing therethrough. 00

My invention is also capable of use to advantage in the manufacture of producer gas from comminuted solid fuel, such as pulverized coal. Some slight changes are, however, advisable in the construction of the producer units, when this kind of fuel is employed. Such modifications are illustrated in Figs. 5, 6 and 7. In these figures, corresponding parts are given the same reference characters as in Figs. 1 to 4, inclusive, with the letter "a" applied. The combustion chamber 3^a is preferably of circular form and the comminuted fuel is injected into this chamber, preferably under air pressure through the tangentially directed inlet opening 21. The bottom of the combustion chamber is also preferably provided with an ash-collecting hopper 22, and ash-discharge opening 22^a, for the purpose of collecting and removing any ash or slag which may be formed in this chamber. A similar ash-collecting hopper 23, having an ash-discharge 24, is also provided in the bottom of the expansion chamber 12^a, for the purpose of collecting and removing the ashes which may be carried over with the gases in the form of dust. The top wall of the combustion chamber is also shown as having a normally closed opening 25, through which waste or other combustible may be introduced into said chamber for the purpose of starting combustion. With these exceptions, the construction of the producer unit and its method of operation is the same as in the form first described. By regulating the amount of fuel, air, etc., introduced into the combustion chamber, the character of the gas formed may be varied within the desired limits.

My invention provides a very effective 130

method by which a superior quality of gas may be produced either from crude oil or from comminuted solid fuel. The carbon deposited by the gases in passing through the producer is utilized for the reduction of carbon dioxid, and the producer chambers and passages are prevented from clogging up with lamp black and other carbon deposits.

10 My invention also provides a producer unit which may be constructed and maintained at a relatively low cost, which may be made of any desired capacity, and which is of compact form.

15 I claim:

1. The method of making producer gas, consisting in injecting fuel in comminuted form by means of steam into a combustion chamber, supplying air thereto and burning the same passing the products of combustion through a contracted passage into an expansion chamber, then passing the expanded products into a reduction tube in contact with incandescent carbon on the walls thereof, and then injecting steam into said gases, substantially as described.

2. The method of making producer gas, consisting in injecting fuel in comminuted form by means of steam into a combustion chamber, supplying air thereto and burning the same passing products of combustion through a contracted passage into an expansion chamber, expanding the products therein to at least five times their initial volume, then passing the expanded products into a reduction tube in contact with incandescent carbon on the walls thereof, and then injecting steam into said gases, substantially as described.

3. The method of making producer gas, consisting in injecting fuel in comminuted form by means of steam into a combustion chamber, supplying air thereto and burning the same passing the products of combustion through a contacted passage into an expansion chamber, then passing the products through a contracted passageway into another expansion chamber, expanding the gases a second time therein, and then passing them through a reducing channel of relatively small area in contact with incandescent carbon on the walls thereof, substantially as described.

4. The method of making producer gas, consisting in injecting fuel in comminuted form by means of steam into a combustion chamber, supplying air thereto and burning the same passing the products of combustion through a contracted passage into an expansion chamber, then passing the products through a contracted passageway into another expansion chamber, expanding the gases a second time therein, then passing them through a reducing channel of relatively small area in contact with incandes-

cent carbon on the walls thereof, and then injecting steam into said gases, substantially as described.

5. The method of making producer gas, consisting in atomizing oil by steam injector 70 action within a combustion chamber, supplying air thereto and burning the same passing the products through a contracted channel into an expansion chamber, expanding the gases therein, and then feeding them 75 through a reducing tube of relatively small area and in contact with incandescent carbon on the walls thereof, and then introducing steam into said products, substantially as described.

6. The method of making producer gas, consisting in injecting fuel in comminuted form by means of steam into a combustion chamber, supplying air thereto and burning the same passing the products of combustion 80 through a contracted passage into an expansion chamber, then passing the expanded products into a reduction tube in contact with incandescent carbon on the walls thereof, then injecting steam into said gases, and subjecting the apparatus to such artificial draft that the flow of gas through the apparatus occupies not less than three seconds, substantially as described.

7. A gas producer comprising a combustion chamber, means for introducing fuel in comminuted form into said chamber and for thoroughly mixing the same with steam, the producer having a contracted passage leading from the combustion chamber and connected to an expansion chamber of relatively large volume, an elongated reducing passage leading outwardly from the expansion chamber and adapted to be maintained at a relatively high temperature, and means for 95 introducing a further quantity of steam into the gases after they have passed through at least a portion of the reducing passage, substantially as described.

8. A gas producer comprising a combustion chamber, means for introducing fuel in comminuted form into said chamber and for thoroughly mixing the same with steam, the producer having a contracted passage leading upwardly from the combustion chamber, 100 an expansion chamber into which said passage opens, a second expansion chamber connected with the first expansion chamber by another contracted passage, and a relatively 105 long reduction passage opening out of the last named expansion chamber, said chambers and passages being arranged to give two relatively large successive expansions to the gases before they enter the reduction passage, substantially as described.

9. A gas producer comprising a combustion chamber, means for introducing fuel in comminuted form into said chamber and for thoroughly mixing the same with steam, the producer having a contracted passage lead. 110 115 120 125 130

ing upwardly from the combustion chamber, an expansion chamber into which said passage opens, a second expansion chamber connected with the first expansion chamber by another contracted passage, and a relatively long reduction passage opening out of the last named expansion chamber, said chambers and passages being arranged to give two relatively large successive expansions to the gases before they enter the reduction

passage, together with means for introducing steam into the reduction passage, substantially as described.

In testimony whereof, I have hereunto set my hand.
